[57] CLAIM

The ornamental design for a razor blade assembly, substantially as shown and described.

DESCRIPTION

FIG. 1 is a perspective view of a razor blade assembly showing my new design;
 FIG. 2 is a top plan view thereof;
 FIG. 3 is a bottom plan view thereof;
 FIG. 4 is a front elevational view thereof;
 FIG. 5 is a rear elevational view thereof; and
 FIG. 6 is a left side elevational view, the opposite side being substantially a mirror image thereof.
